on frame 53. Preferably, and as shown, the machine is provided with two sets of indications on the movable conical portion and two corresponding index points on the cooperating non-movable frame which permits of ready reading of the burr setting by the clerk on one side of the machine and the customer on the other; the indications naturally being, in such case, so arranged as to be readily read from the opposite 10 positions, as desired; the indications on the rotary member being shown as indicating letters corresponding to the setting of the grade selector mechanism. The hand wheel has a centrally located aperture through which there extends a 15 screw head 54 formed integrally with a disk 55 which disk is attached to a sleeve member 56 by means of a plurality of screws 57. The sleeve is provided with internal screw threads 58 and is rotatably mounted within the hollow projecting 20 flange of the stationary frame 53 with interposed bearing members 59 so that the sleeve 56 is freely rotatably mounted but is held against axial movement.

The sleeve 56 engages with a threaded shaft 60 which is provided with a non-circular end portion 61 which extends through a cooperatively formed non-circular recess in the frame member 53, thereby providing for axial movement of the shaft 60 while preventing rotational movement 30 thereof. A suitable contact or thrust member 62 is attached to the end of shaft 60 for engagement with the cup shaped member 36 which encloses the end of the shaft 35 and the surrounding hub of the burr 33, whereby controlled axial 35 movement of the member 60 effects desired adjustment of the movable burr 33.

As shown the members 56 and 60 are provided with quick threads,—in the form shown multiple threads—to give increased relative axial 40 movement for a given angular rotation to thus permit of effecting the entire range of burr adjustments within the normal turning range of a single hand movement—that is, within an angular range of 180°. Also, this is of advantage 45 where two sets of indications are desired to be used, as above described.

From the above it will be clear that when the hand wheel 50 is rotated, sleeve 56 is likewise rotated and is held in fixed axial position by 50 means of the bearing members 59. Rotation of sleeve 56 produces axial movement of non-rotating shaft 60, toward or away from the movable burr 33 to provide for moving such burr closer to or farther from the stationary burr 32 and thereby to control the fineness of the grind.

A locking disk 65 is seated upon the sleeve 56 and is adapted to engage, and frictionally lock with, a shoulder 66 formed thereon and to be drawn up against such shoulder by means of a 60 plurality of locking screws 67. When these screws are tightened, sleeve 56 is retained in a predetermined relationship with the hand wheel 50, but upon the loosening of the locking screws 67, the sleeve may be adjusted with respect to 65 the hand wheel 50 by means of the screw head 54 to thereby properly adjust the position of the burr with respect to the indications.

Means are provided for normally tending to move the grade selector means in such direction as 70 to adjust the burrs to their largest spacing, or to a non-grinding position. This means comprises an annularly arranged spiral spring 70 slidably held, within a groove 71, in the conical portion 51 of the hand wheel. One end of the spring 75 abuts against a pin 73 fixed in the frame 53, and

the other end of the spring is engaged by a pin 72 carried by the hand wheel. Pin 72 engages with the end of the spring and upon turning of the hand wheel causes compression of the spring sufficient to return the grade selector means to its off or non-grinding position when the hand wheel is released. The spring is preferably pre-loaded, being of such length as to be under compression when the burrs are in the non-grinding position, i. e., "off" position of the hand wheel 10 indications; and the pins 72—73 are located out of line, so that as the spring expands to this "off" position each pin 72—73 will control the other end of the spring which thus acts as its own energy absorber. 15

Means are provided for requiring an operation of the grade selector means away from the off position to a grinding position before the mill can be started. Since this preliminary operation of the grade selector to a grinding position is 20 required each time the mill is operated, there is more assurance that the operator will adjust the mill in accordance with the wishes of each individual customer. This means comprises an interlock member 75 pivotally mounted upon pin 25 76 attached to the frame 53 and having an extended end portion 77 adapted to ride upon the outside surface of the flange portion 51a of the hand wheel toward which it is urged by spring 78. The disk 79 attached to and rotatable with 30 shaft 16 and the handle 18 which controls the grinding operation, is provided with a notch 80 adapted to receive the opposite end 81 of the interlock member. The flange portion 51a is provided with a cut-away portion 82 which moves 35 under the end 77 of the interlock when the grade selector is turned to reach the off or non-grinding position; this opening being sufficiently wide to permit oscillation of the hand wheel under the action of the shock-absorbing functioning of 40 the spring 10. In such position the interlock member is turned on its pivot by means of spring 78 and the end 81 is caused to engage within the notch 80, thereby locking the handle 18 and preventing its movement toward on position while 45 the grade selector remains in non-grinding position. Upon rotation of the hand wheel to any one of the predetermined grinding positions, the surface of 51a engages the end 77, causing the withdrawal of the member 81 from the notch 80, 50 after which the control handle 18 can be turned to the "on" position to start the operation of the mill, i. e. to start the motor and to open the gate for the admission of coffee to the mill. As shown the spring 78 is coiled about the pin 76 55 with one end bent about a pin 83 and the other end extended against a fixed lug or abutment 84, to urge the end portion 77 at all times toward the hand wheel.

Means are provided for latching the hand wheel 60 in any of its predetermined grinding positions. This means comprises a plurality of notches 85 formed between ratchet teeth on the interior of the flange portion 51a of the hand wheel. A latch member 86 is mounted upon a pivot pin 87 65 which is carried by the frame 53. A suitable spring 88 urges the end portion 89 of the latch upwardly into the path of the teeth 85, and so into latching position. These teeth are formed of such contour that the hand wheel can be 70 turned in one direction, clockwise as viewed in Fig. 3, without interference from the latching member. However, the latch, which engages successively in each of the several notches and against the several teeth, will hold the hand wheel 75

in any one of these predetermined positions against movement in the opposite direction, i. e., toward the coarser and non-grinding positions. Preferably the notches are so positioned as to correspond to the several degrees of fineness desired, for instances, "coarse", "medium", "fine" and "very fine". As shown the spring 88 is coiled about the pivot pin 87 with one end hooked about a pin 88a carried by the latch 86 and the other end abuts against the adjacent portion of 53 and the tension is such as to urge the latch toward the notches between the teeth 85.

Release means is provided for the latching mechanism which is interrelated with the control handle 18 for controlling the operation of the mill, this interlocking means providing for the release of the latching mechanism only when the control handle 18 is moved into such position as to stop the operation of the mill. This means includes the disk 79, rotated with handle 18, which is provided with a cam surface 90 shown in dotted lines in Fig. 3 which cooperates with a cam follower 91 suitably mounted within frame 53. Spring 92 retains member 91 in engagement with the cam surface at all times. The member 91 is provided with an outwardly extending finger 93, extending through a slot 94 formed in the frame member 53, which is adapted to engage a tongue 95 formed upon the end of the latch arm 30 86.

In the position shown in Fig. 3, the grade selecting means has been adjusted to a grinding position, and the latch 86 retains the parts in such predetermined adjusted position, the control handle 18 being indicated in dotted lines for the on position. In this position the cam follower 91 has moved to its upper limit of travel and the finger 93 does not depress the tongue 95, the end 89 of the latching member therefore remaining 40 in the latching position. At the end of the grinding operation, the handle 18 is moved to the "off" position indicated in dotted lines in Fig. 4 (stopping the grinding operation), where the cam follower 91 is cammed downwardly, the finger 93 depressing tongue 95, to thereupon cause the disengagement of the end 89 of the latching member from the notches 85, allowing the hand wheel to be returned to its extreme end or non-grinding position by means of spring 10, which also absorbs 50 the shock of return when the hand wheel is released, as described above.

A reset mechanism comprising a pin 98 mounted within the frame 53 and spring pressed outwardly, provides for withdrawal of the latch 86 when it is desired to momentarily release the latch from latching engagement, as for the resetting of the grade selector to a coarser position. As will be obvious, no reset mechanism is required when the hand wheel is moved from a 60 coarser to a finer position as the latching means does not prevent such movement.

From the above it will be clear that the interlock member 75 and its associated parts prevent starting of the mill until the grade selector means has been adjusted to a predetermined one of the grinding positions. When so adjusted the control handle can be moved to on position and the mill placed in operation, the grade selector mechanism being retained in the selected position. At the 70 end of the grinding operation the control handle is turned to the off position, opening the motor switch and closing the gate, and simultaneously releasing the latching mechanism to permit the grade selector to be returned to its non-grinding position under the influence of spring 10, in which

position the interlock 75 again becomes effective as above described.

In order to restore the action of the latching mechanism 86 when the mill has been stopped, so that the grade selector will be retained in any 5 adjusted position prior to the opening movement of the handle 18, means are provided for disabling or withdrawing the action of the releasing finger 93 when the grade selector has been returned to non-grinding position. To accomplish this result, the pivot 87 for the latch 86 is provided with an enlarged curved bearing surface 100 so that the latch member, in addition to its pivotal movement, may having a rocking or swinging movement about the enlarged bearing surface. A 15 cam member 101 carried upon the inner face of hand wheel 51 is adapted to engage the end portion 102 of the latch 86 when the hand wheel has been returned substantially to its end or non-grinding position. This engagement, as shown 20 in Fig. 6, produces a lateral swinging of the latch member on its pivot and withdraws the tongue 95 from the path of the finger 93 allowing the spring 88 to return the latch into latching relationship with the notches 85 which are of sufficient width to provide for such engagement. Thus the release means, 91 etc., is disabled, and the latch is thereupon restored to latching position under the action of its spring 88 when the grade selector is moved back to its non-grind 30 position. Under this setting the latch assumes the described lateral position to be effective to retain the hand wheel in any predetermined grinding position irrespective of the release means 35 91, etc. which is then disabled, while the handle 40 is also locked against turning by the latch 75 and the grinding mechanism is locked until the grade selector is thereafter moved to one of the grinding settings. When another grinding operation is to be performed, the operator will move the hand wheel to the desired grinding position which rocks the latch 75 and then permits movement of the handle 18 to start the motor. When the hand wheel is moved away from its neutral position, cam 101 is withdrawn from engagement with 45 latch portion 102, and when finger 93 is moved to its upper position in response to operation of handle 18 to start the motor, spring 88 acts to rock latch 86 bodily about its curved pivot to thereby restore latch 86 to its initial position 50 where it will again be in position to be engaged by finger 93 upon subsequent downward movement thereof. As the hand wheel remains in any set position, he will normally set the grade selector and then the handle 18 to start the mill, 55 thus avoiding the necessity for utilizing two hands in the operation of the mill.

It is believed that the operation of the device will be clearly apparent from the above. Coffee is placed in the hopper 13 from a suitable container, the gate 15 being closed to retain the coffee in the hopper. If desired, the same container may then be positioned below the discharge outlet 47 to receive the ground coffee. The customer's wishes having been ascertained, 60 the hand wheel is adjusted to the desired grinding position, and is retained there by the latching mechanism. If the adjustment must be changed, the reset pin 98 may be operated to return the hand wheel toward its coarser positions. 70

The grade selector mechanism having been adjusted to the proper operating position, the control handle 18 may be turned to its on position whereupon the motor switch is closed and the gate opened to admit coffee to the grinding 75

mechanism of the mill which discharges a homogeneous ground material of predetermined fineness into the container.

At the end of the grinding operation the handle 18 is turned to the off position, resulting in the unlatching of the grade selector which thereupon is returned to its non-grinding position. In such non-grinding position the interlock becomes effective to prevent a subsequent operation 10 of the control handle 18 until the grade selector mechanism has been adjusted to a predetermined grinding position.

Figs. 7 and 8 show an arrangement adapted for a mill having a single driving motor, two separate hoppers, and two separate grinding means. Such a mill, sometimes known as a double ended mill, may have the same grinding means at each end, or may have different means providing for grinding to different grades of fineness. The 20 present invention provides for the controlled operation of a double ended mill in a manner similar to that described above for the single ended mill.

The motor 120 is arranged substantially centrally of the casing 121 and is provided with a pair of overhanging shafts 122. Grinding means 123 of the construction described above, are suitably mounted and operated by the respective shafts in the manner described above. Separate 30 hoppers 124 are associated with the respective grinding means, admission of the coffee to the hoppers and the grinding means being controlled respectively by the gates 15'. The gates are mounted upon shafts which are actuated by control handles 18'.

Grade selecting means are positioned at each end of the machine, each of which may be constructed in exactly the same manner as described in detail above for the single-ended mill. The 40 detailed construction of the interlocking mechanism is preferably a duplicate of that described above for the single-ended mill, and further description is therefore unnecessary.

Means are provided for controlling the actuation of the motor from either end of the mill. 45 For this purpose the shafts 16' are provided with crank arms 22' to which are connected operating rods 132, each rod being provided with a link 133 having an elongated slot 134 formed therein. The motor switch 135 is preferably positioned 50 between the rods 132 and spring means 136 tends to yieldingly urge the switch toward the off position. The switch is provided with an operating member 137 which carries a cross bar 138 having 55 sliding engagement in both slots 134. The construction is such that when both control handles 18' are in the off position, as illustrated for instance by the left hand end of the mill in Fig. 7, links 133 are drawn upwardly and the spring 60 136 causes the operation of the switch arm 137 to "off" position. However, upon the operation of either or both control handles to "on" position, illustrated in the right hand end of the mill of Fig. 1, link 133 engages the rod 138 to cause actuation of the switch to the on position. The 65 elongated slot in the link prevents interference of the one operating rod with the other, providing for the actuation of the motor switch to on position when either operating handle is moved to on position.

As will be clearly evident from the foregoing description, this arrangement provides for the same controlled interlocking of the grade selector mechanism with each control handle as with a 75 single ended construction. Before the control

handle at either end of the mill can be adjusted to the on or grinding position, the corresponding grade selector must have been previously moved to a predetermined grinding position. This movement of the grade selector releases the interlock from the operating handle, which can then be turned to the on position, opening the gate and starting the motor. At the end of the grinding operation, the control lever is moved to the off position, which releases the grade selector mechanism which thereupon is returned to the off or non-grinding position by its resilient means. Movement of the control handle at one end of the mill to the off position also effects the closing of the associated gate, and the stopping of the motor provided the other end of the mill is not in operation. In case the other end of the mill is in operation, the motor will not be stopped until both control handles are turned to the off position, but a subsequent operation of that end of the mill and the opening of its gate will be prevented until after the grade selector mechanism at that end has been readjusted to a desired grinding position.

While the forms of apparatus herein described 25 constitute preferred embodiments of the invention, it is to be understood that the invention is not limited to these precise forms of apparatus, and that changes may be made therein without departing from the scope of the invention which 30 is defined in the appended claims.

What is claimed is:

1. A coffee mill of the character described comprising a housing, a motor, grinding means driven by said motor and located within said housing, 35 grade selector means for said grinding means adjustable from a non-grinding position to a plurality of grinding positions, resilient means effective to move said grade selector means to non-grinding position, releasable means inaccessable within said mill for retaining said grade selector means in any selected grinding position against return movement, and reset means accessible from outside said casing for releasing said retaining means to provide for the readjustment of said grade selector means. 40

2. A coffee mill of the character described comprising a motor, grinding means driven thereby, grade selector means for said grinding means adjustable from a non-grinding position to a plurality of grinding positions, means tending to move said grade selector means to said non-grinding position, releasable means for retaining said grade selector means in any predetermined grinding position, means for controlling the grinding of coffee, means operable upon the actuation of said controlling means to stop the grinding of coffee for releasing said retaining means to allow said grade selector means to return to said non-grinding position, and means 50 effective upon the return of said grade selector means to said non-grinding position for disabling the action of said releasing means. 55

3. A coffee mill of the character described comprising a motor, a motor switch having an operating member, grinding means driven by said motor, grade selector means for said grinding means adjustable from a non-grinding position to any one of a plurality of grinding positions, means tending to move said grade selector to non-grinding position, said means comprising a coiled spring under compression, and relatively movable means connected to the opposite ends of said spring arranged to overrun after the grade selector means is moved to off position 70 75

whereby the said spring acts to absorb the energy of movement, releasable means for retaining said grade selector means in any selected grinding position and means operated by the 5 motor switch operating member for releasing said retaining means, whereby the grade selector means will be returned to off position under the action of said spring.

4. A coffee mill of the character described, comprising a motor, grinding means, grade selector means for said grinding means adjustable from a non-grinding position to a plurality of grinding positions, a motor switch and a handle for operating said switch positioned adjacent said 10 grade selector means, a stop pawl positioned adjacent said handle with one end cooperatively engaged with the said grade selector means, and the other end adapted to be moved into stopping engagement with a stop member upon said 15 handle, means for urging said pawl into stopping engagement with said stop member, and means carried by said grade selector effective upon said pawl within a predetermined portion 20 of the range of movement of said grade selector member to move said pawl out of locking engagement with the said motor switch handle, said means being positioned to move said pawl out of locking engagement after the grade selector means is moved from the off position to the first 25 grinding position.

5. A coffee mill of the character described comprising motive means, a plurality of hoppers, a plurality of grinding means driven by said motive means and associated respectively with said 30 plurality of hoppers, gate means for controlling admission of coffee from each hopper into its associated grinding means, grade selector means for each grinding means adjustable from a non-grinding position to a plurality of grinding positions, means tending to move each grade selector 35 means to its non-grinding position, releasable means for locking each said grade selector means in any of its selected grinding positions, means effective upon the closing of any of said gate 40 means for releasing the associated locking means to allow the grade selector means associated therewith to return to its non-grinding position, and means preventing a subsequent opening of a 45 closed gate means until after the adjustment of the grade selector means associated therewith to a grinding position.

6. A coffee mill of the character described comprising motive means, a plurality of hoppers, a plurality of grinding means driven by said motive means and associated respectively with said 50 plurality of hoppers, gate means for controlling admission of coffee from each hopper into its associated grinding means, grade selector means for each grinding means adjustable from a non-grinding position to a plurality of grinding positions, means tending to move each grade selector 55 means to its non-grinding position, releasable means for locking each said grade selector means in any of its selected grinding positions, means effective upon the closing of any of said gate 60 means for releasing the associated locking means to allow the grade selector means associated therewith to return to its non-grinding position, means preventing a subsequent opening of a 65 closed gate means until after the adjustment of the grade selector means associated therewith to a grinding position, and means effective when any of said gate means is opened for starting said 70 motive means and for stopping said motive means 75

when none of said gate means is in open position.

7. In a coffee mill provided with a motor, grinding means operated thereby, grade selector means for said grinding means adjustable from a non-grinding position to a plurality of grinding 5 positions, resilient means effective to move said grade selector means to non-grinding position, a motor switch, a gate for controlling the admission of coffee to said grinding means, and a common control member for said gate and said switch providing for opening movement of said gate concomitantly with closing movement of the switch, means effective for controlling the operation of said mill comprising latching means 10 for retaining the grade selector means in any selected grinding position against return movement prior to operation of said control member to effect the closing of said gate and the opening of said switch member, and means operable upon closing said gate for withdrawing said latch means from latching position to provide for return of said grade selector to non-grinding 15 position.

8. A coffee mill of the character described comprising a motor, grinding means, grade selector means for said grinding means adjustable from a non-grinding position to a plurality of grinding positions, means tending to move said grade selector means to non-grinding position, and retaining 20 means for preventing movement of said grade selector means from a grinding position toward a coarser grinding position while permitting movement thereof toward a finer grinding position.

9. A coffee mill of the character described comprising a motor, grinding means, grade selector means for said grinding means adjustable from a non-grinding position to a plurality of grinding positions, means tending to move said grade selector means to non-grinding position, retaining means for preventing movement of said grade selector means from a grinding position toward a coarser grinding position while permitting movement thereof toward a finer grinding position, and means under the control of the operator for releasing said retaining means to provide for the return of said grade selector means toward a coarser grinding position and toward 30 said non-grinding position.

10. A coffee mill of the character described comprising a motor, grinding means, a gate for controlling the introduction of coffee to said grinding means, grade selector means for said grinding means adjustable from a non-grinding position to a plurality of grinding positions, means tending to move said grade selector means to non-grinding position, retaining means for preventing movement of said grade selector means from a grinding position toward a position of coarser grind while providing for movement 55 thereof toward a position of finer grind, and means controlled in response to movement of said gate toward closed position for releasing said retaining means and providing for the return 60 of said grade selector means to non-grinding 65 position.

11. A mill of the character described comprising a motor, a motor switch, grinding means operated by said motor, grade selector means for said grinding means adjustable from a non-grinding position to a plurality of grinding positions, resilient means effective to move said grade selector means to non-grinding position, a gate for controlling admission of material to be ground 70 to said grinding means, a control means for said 75 grinding means,

gate and said motor switch operable from an off position to an on position to open said gate and energize said motor, and latching means operative when said control means is in off position 5 and during the subsequent movement thereof to on position for retaining said grade selector means in any selected grinding position against return movement.

12. A mill of the character described comprising 10 a motor, grinding means, grade selector means for said grinding means adjustable from a non-grinding position to a plurality of grinding positions, resilient means effective to move said grade selector means to non-grinding position, a gate for controlling admission of material to be ground to said grinding means, latching means operative when said gate is in closed position and during the subsequent movement of the gate to open position for retaining said grade selector means in any selected grinding position against return movement, and means operable upon the closing of said gate for effecting withdrawal of said latching means to provide for return of said grade selector means to non-grinding 25 position.

13. In a mill of the character described provided with a motor, a motor switch, grinding means operated by said motor, grade selector means for said grinding means adjustable from a non-grinding position to a plurality of grinding positions, resilient means effective to move said grade selector means to non-grinding position, and latching means operable when said switch is in circuit opening position and during the subsequent closing thereof for retaining said grade selector means in any selected grinding position against return movement.

14. In a mill of the character described provided with a motor, a motor switch, grinding means, grade selector means for said grinding means adjustable from a non-grinding position to a plurality of grinding positions, resilient means effective to move said grade selector means to non-grinding position, latching means operable when said switch is in circuit opening position and during the subsequent closing thereof for retaining said grade selector means in any selected grinding position against return movement, and means operable upon the opening of said switch for effecting withdrawal of said latching means to provide for return of said grade selector means to non-grinding position.

15. A mill of the character described provided with a motor switch means therefor, grinding means, grade selector means for said grinding means adjustable from a non-grinding position to a plurality of grinding positions, resilient means effective to move said grade selector means to non-grinding position, latching means for retaining said grade selector means in any selected grinding position against return movement, means operable upon operation of said switch to open circuit position for effecting withdrawal of said latching means to provide for return of said grade selector means to non-grinding position, and means operable in the non-grinding position of said grade selector for restoring the action of said latching means in preparation for a subsequent cycle of operation of the mill.

16. A mill of the character described provided with a motor, grinding means, grade selector means for said grinding means adjustable from a non-grinding position to a plurality of grinding

positions, resilient means effective to move said grade selector means to non-grinding position, a gate for controlling admission of material to be ground to said grinding means, latching means for retaining said grade selector means in any selected grinding position against return movement, means operable upon closing of said gate for effecting withdrawal of said latching means to provide for return of said grade selector means to non-grinding position, and means operable in the non-grinding position of said grade selector for restoring the action of said latching means in preparation for a subsequent cycle of operation of the mill.

17. A coffee mill of the character described comprising a motor, grinding means driven thereby, grade selector means for said grinding means adjustable from a non-grinding position to a plurality of grinding positions, means tending to move said grade selector means to said non-grinding position, releasable means for retaining said grade selector means in any predetermined grinding position, means for controlling the grinding of coffee, means operable upon the actuation of said controlling means to stop the grinding of coffee for releasing said retaining means to allow said grade selector means to return to said non-grinding position, and means effective upon the return of said grade selector means to said non-grinding position for disabling the action of said releasing means.

18. A coffee mill of the character described comprising motive means, a plurality of hoppers, a plurality of grinding means driven by said motive means and associated respectively with said plurality of hoppers, gate means for controlling admission of coffee from each hopper into its associated grinding means, grade selector means for each grinding means adjustable from a non-grinding position to a plurality of grinding positions, means tending to move each grade selector means to its non-grinding position, releasable means for locking each said grade selector means in any of its selected grinding positions, and means effective upon the closing of any of said gate means for releasing the associated locking means to allow the grade selector means associated therewith to return to its non-grinding position.

19. A coffee mill of the character described comprising motive means, a plurality of hoppers, a plurality of grinding means driven by said motive means and associated respectively with said plurality of hoppers, gate means for controlling admission of coffee from each hopper into its associated grinding means, grade selector means for each grinding means adjustable from a non-grinding position to a plurality of grinding positions, means tending to move each grade selector means to its non-grinding position, releasable means for locking each said grade selector means in any of its selected grinding positions, means effective upon the closing of any of said gate means for releasing the associated locking means to allow the grade selector means associated therewith to return to its non-grinding position, and control means for causing operation of said motive means to drive said grinding means when any of said gate means is in open position and for stopping said motive means when none of said gate means is in open position.

DAVID A. MEEKER.
